112,124

DESIGN FOR A HEATER CASING

Carl E. Meyerhoefer, Brooklyn, N. Y., assignor to
E. A. Laboratories, Inc., Brooklyn, N. Y., a cor-
poration of New York

Application March 18, 1938, Serial No. 75,914

Term of patent 14 years

To all whom it may concern:

Be it known that I, Carl E. Meyerhoefer, a citizen of Germany, residing at Brooklyn, in the county of Kings and State of New York, have invented a new, original, and ornamental Design for a Heater Casing, of which the following is a specification, reference being had to the accompanying drawing, forming a part thereof, wherein:

Fig. 1 is a right hand perspective view of a heater casing showing my new design; and
Fig. 2 is a left hand perspective view thereof.

I claim:

The ornamental design for a heater casing, as shown.

CARL E. MEYERHOEFER.
